UNITED STATES PATENT OFFICE.

PAUL M. LINCOLN, OF PITTSBURGH, PENNSYLVANIA.

ENGINE STARTING DEVICE.

1,290,598.

Specification of Letters Patent.

Patented Jan. 7, 1919.

Application filed February 3, 1913. Serial No. 745,824.

To all whom it may concern:

Be it known that I, PAUL M. LINCOLN, a citizen of the United States, residing at Pittsburgh, in the State of Pennsylvania, 5 have invented a certain new and useful Engine Starting Device, of which the following is a specification.

My invention relates more particularly to devices for starting explosive engines such 10 as used on automobiles by means of an electric motor, its primary object being to render such devices more efficient and certain and safe in their operation. I have illustrated one embodiment of the invention in 15 the accompanying drawing in which the figure diagrammatically represents, in vertical cross-section, a casing containing the engine shaft and the starting motor and appliances for operating it.

20 Briefly, I provide means for throwing a switch to start an electric motor and at the same time making a temporary engagement between the shaft of the motor and a gearing designed to turn over the engine shaft, 25 combined with devices for automatically disengaging the two elements after the engine starts. For example, in the drawing, supposing the shaft 3 to be the shaft of an explosive engine, it will be understood that 30 giving it a few turns in the right direction causes an explosion in the engine cylinder and the starting up of the engine. The shaft 3 carries a gear 4 which normally is free of engagement, but is arranged in close prox- 35 imity to a worm gear 5 splined upon the horizontal shaft 6 of an electric motor 7 attached to the casing 2. The worm 5 is normally held in the position shown in full lines by means of retractile springs 8, but it may 40 be moved toward the left by manual operation as follows:

On its hub are mounted clutch fingers 9 which are attached to rods 10 extending into the supplemental casing 13 containing the 45 electric starting device.

The rods 10 may be attached to a head 12 which rigidly carries a stiff spring 11 pro- 50 vided with a notch 14 engaging the head 15 of a horizontally slideable rod 16. Nor- 55 mally, this rod 16 is held in position toward the right by retractile spring 30 and re- tained at a fixed position by the fixed collar 17 thereon abutting a partition 13^a of the casing. When it is desired to start the de- 60 vice, the rod 16 is drawn to the left in any convenient manner by the operator, a bell-

crank lever 25, a rod 26 and a knob 27 be- 60 ing shown as constituting a suitable means for this purpose and the first action is to cause the collar 17 to engage the spring 18 mounted in and insulated from the casing 13 as shown. Depressing the spring 18 causes a contact between it and the conduct- 65 ing plate 19 while the upper end of the spring 24 remains free. This closes the elec- 70 tric circuit from battery 23 through the leads shown and the spring 18, resistance 20, contact 21, and leads 22 and 22^a to the motor 7. The resistance 20 is not essential but is here inserted because at this stage it is not necessary to have the full power of the motor; just at the moment when the contact 18, 19 is made the worm wheel 5 will have been brought into mechanical engagement 75 with the gear 4 and as the motor shaft 6 be- 75 gins to turn, the worm 5 instead of turning the wheel 4 will simply push itself along the shaft 6 until it abuts against the end of the casing 2 as shown in dotted lines. At this point the worm will necessarily begin to 80 turn the wheel 4 and shaft 3 of the engine; and at this time also the continued move- 85 ment to the left of the shaft 16 and collar 17 will bring the latter against the head 24 of the spring 18 making contact at 21 and thus cutting out the resistance 20 will throw the full current onto the motor 7.

The engagement between the worm 5 and the shaft 16 is preferably made so that the worm will be set free to return to initial po- 90 sition as soon as possible and to this end I form an extension 28 on the spring 11 so as to abut against the spur 29 on the partition 13^a and by depressing disengage the spring 95 from the head 15 of the shaft 16. Of course, as soon as the engine starts, the worm 5, instead of continuing to drive the gear 4, will be itself driven back to the right and disengaged by the movement of gear 4 itself. The rod 16 will be returned to initial posi- 100 tion by the spring 30 as soon as released by the operator and this of course will stop the electric motor.

In order to insure the retardation of the spark, in starting the explosive engine, I 105 may provide on the collar 17 and extending through a slot in the casing 13, a rod 31 which, by a link 32, may be connected to the spark lever and turn it toward the retarding position, which action will insure the engine 110 rotating in the proper direction as soon as explosions take place. Since the rod 16

makes its whole travel each time it is operated, this arrangement will bring the spark lever to its retarded position no matter where it may be when the travel of rod 16 begins.

It will be noted that by the above described device, the proper starting of the engine is not dependent upon any complicated mechanism or elaborate electric switches that can get out of order and all danger of failure to properly disengage the motor and the engine shaft is obviated. At any time the engine shaft begins to move, the connection with the starting motor is eliminated by the engine's own movement, nor will the accidental continuation of the operation of the motor have any effect. The whole apparatus is easily inclosed in dirt-proof casings and the electric switches are sure of operating and under direct control of the operator. Various other advantages of the device will occur to those familiar with the art. The references in the claims to manual or hand operation are intended to be generic; voluntary operation by the driver of the car, whether by hand or foot power, being commensurate with the scope of the invention.

Having thus described my invention and illustrated its use, what I claim is the following:

1. The combination of an engine and its shaft, an actuating electric motor to operate the engine, a switch in the motor circuit a slidable gear member on the motor shaft, re-

silient means serving to bias said gear member toward its inactive position, a gear member on the engine shaft adapted to be engaged by the said slidable gear member when the latter is adjusted to operative position, said gear members being automatically disengaged when the engine shaft is driven by the engine, separable members serving to effect initial engagement of the two said gear members and to actuate the motor-circuit switch to first close the circuit and then to reduce the resistance thereof, and means for separating said members upon completion of the gear-engaging and switch-actuating functions.

2. The combination with an electric motor and a longitudinally movable gear member carried by its shaft, of an engine, a gear member rigidly mounted on its shaft, a motor-energizing circuit, an actuating means serving to effect engagement of said gear members and to close said energizing circuit and, upon further movement, to increase the power of the motor by cutting out a resistance in its circuit and then to release the movable gear member, substantially as described.

In testimony whereof I have hereunto signed my name in the presence of the two subscribed witnesses.

PAUL M. LINCOLN.
